UNITED STATES PATENT OFFICE.

HERMAN N. KENNEDY AND BURR A. KENNEDY, OF CHICAGO, ILLINOIS.

HARVESTING-MACHINE.

SPECIFICATION forming part of Letters Patent No. 351,181, dated October 19, 1886.

Application filed October 19, 1885. Serial No. 180,276. (No model.)

To all whom it may concern:

Be it known that we, HERMAN N. KENNEDY and BURR A. KENNEDY, citizens of the United States, residing at Chicago, in the county of Cook and State of Illinois, have invented certain new and useful Improvements in Harvesting-Machines, of which the following specification contains a full description.

This invention relates to the construction of the frame of a harvesting-machine, and comprises devices for securing front and rear sills or frame-bars formed of tubular metal to the trusses which extend from front to rear, and in the construction of a gearing-frame in form to serve as the struts for the trusses.

In the drawings, Figure 1 is a stubble side elevation of the frame and gearing, the drive-wheel and main driving-gear being shown in dotted lines. Fig. 2 is a plan. Fig. 3 is a perspective of the gearing-frame. Fig. 4 is a detail perspective of one of the truss-clasps embracing the tubular sill.

A is the rear sill.

A' is the front sill.

B is a shoe bolted rigidly to the inner end of the front sill, and affording an attachment for the finger-bar B', which is bolted rigidly to it behind the front sill, A'.

C' is the outer side truss. C² and C³ are in side trusses. They may be each formed of one piece of iron bent around the sills A A', so as to pinch onto them; but in construction it is more convenient to make the portion which forms the angle and clasps and pinches the tubular sills of a separate piece. These clasps c are preferably wider than the upper and lower bars, c² c³, of the trusses, in order to give them a firmer grasp upon the tubular sills. This grasp is strengthened by the clamping or pinching bolts c', which are passed through both leaves of the clasp, inside of and close against the sills, and secured by exterior nuts, c⁵. Further, to strengthen the grasp of the clasps on the sills and prevent "winding" of the frame by the clasps slipping around on the sills, and at the same time prevent them from moving longitudinally on the sills, the bolts c' are passed through the clasp at the bend which embraces the sill, and through

both walls of the tubular sill, and securely headed at both ends, thus forcing the tubular sill firmly into the bend of the clasp. The

segments D D form center struts for the trusses C' and C². The outer truss, C', not being subjected to the strain of the gearing, requires no further struts.

E is the gearing-frame. It is made integral with upper and lower flanges to fit the upper and lower bars, c' c², of the trusses C² and C³, and is bolted rigidly thereto, thus not only relieving the trusses and the frame of the greater part of the strain due to the reaction between the gear-wheels of the train, its own rapidity resisting that strain, but in addition serving as the struts for both the inside trusses, very greatly increasing their capacity to carry the dead-weight of the machine and resist the shocks due to travel over uneven ground, and bracing the two trusses apart horizontally, and thereby adding to the transverse rigidity of the entire structure. This gearing-frame will now be described in detail. It comprises the standards E' and E² in the same vertical transverse plane, and connected by the drooping yoke or loop E³. These standards have respectively the horizontal bearings e' and e² for the main pinion-shaft, the lower soles, e¹⁰ and e²⁰, to fit the lower bars, c', of the trusses C² and C³, respectively, and the upper flanges, e¹¹ e²¹ and e¹² e²², to fit the upper bars, c², of said trusses. Protruding horizontally at right angles to the box e² is the box e³, and connected thereto by the arm E⁴ is the box e⁴ in line with the box e³, and provided with lateral wings e³⁰ e⁴⁰, which rest upon the upper side of the upper bars, c² c³, of the trusses C² C³. Through all the flanges e¹⁰ e²⁰ e¹¹ e²¹ and through the wings e³⁰ bolts are passed into and through the truss-bars, thereby very rigidly securing the gearing-frame E to the trusses. The gearing which is sustained upon this frame is not a part of this invention, but will be described in order to make the utility of the frame-work more clear.

F is the main driving gear-wheel, rigid with the drive-wheel G. g is the axle of the drive-wheel, which is loose thereon. Rigid with the axle g are the pinions G', meshing in the racks of the segments in the usual manner. Also rigid with said axle is the sprocket-wheel G².

H is the main pinion, meshing with and driven by the main gear-wheel F. h is the shaft journaled in the boxes e' e² of the gear-

ing frame E. Said shaft is rigid with the pinion H. Loose on said shaft between the pinion H and the box e' is the sprocket-wheel G³, having integral with it the worm-wheel G³⁰. 5 Above the worm-wheel there is secured to the bar c² of the truss C² the bracket J, and journaled therein is the shaft K, having the worm or endless screw K' engaging with the worm wheel G³⁰. Said shaft K is extended to 10 the rear, where it may, if desired, have another bearing, and is provided with a crank-handle, K², by which it may be rotated.

The sprocket-wheel G³ is in the same vertical plane as the sprocket-wheel G², and the 15 endless chain g² passes around both and communicates to the latter wheel the motion which the former derives through the worm K' and worm-wheel G³⁰ from the shaft K when the latter is rotated by the crank K². By this means 20 the frame is raised and lowered without disturbing the relation of the gear-wheel F and the pinion H.

On the shaft h is fixed the bevel gear-wheel H', which revolves in the loop of the yoke E³.

25 In the boxes e³ and e⁴ is journaled the shaft h', which carries on its outer end the sprocket-wheel H², and has running loose on its inner end, next to the box e³, the bevel pinion H³, which meshes with and is driven by the bevel 30 gear-wheel H'. The hub of the pinion H³ is provided with clutch-teeth h³, and on the shaft h', between the box e⁴ and the pinion H³, is placed the clutch H⁶, sliding on and revolving with the shaft h', and having its clutch-teeth h⁵ matched to the teeth h³ on the hub of the 35 pinion H³, and provided with the spring H⁶, tending to hold it in engagement with the said pinion-hub. Any convenient means may be provided to disengage it.

40 The operation of this train of gearing is obvious. The sprocket-wheel H² is employed to communicate motion to the remainder of the mechanism of the harvester. (Not shown.)

In order to afford convenient and secure 45 means of attaching the upright posts which may be needed to uphold the elevated portion of the machinery, the upper bars, c², of the trusses c' and c³ are extended beyond the clasps at the forward end, and may be bent up, as 50 shown at c²⁰, to give greater surface to overlap the posts M, which are bolted onto the vertical flange of the angle-iron bar c².

In order to afford convenient means of attaching the pole, the upper and lower bars, c² and c³, of the truss C² are extended in front of the clasp at the front end of the truss, and the metal block P, having the pivot-stud p for the pole, is firmly bolted between said extended bars. The shoe B is provided with the lug b 55 in line with the block P, and in line with the stud p the said lug has the eye b'. The pole R is pivoted on the stud p and has the brace-rod r hooked into the eye b'.

We claim—

5. 1. In combination with the tubular sills, the trusses forming the connection from front to rear between said sills, made of metal clasped

around and pinched onto said tubular sills, and bolts passing through the walls of the tubular sills and through the embracing truss-irons at the bend, to force the tubular sills into the bend and increase the grasp of the latter on the sill. 70

2. In combination with the tubular sills, the truss-iron clasped around the sill and bolted thereto at the bend, the bolts passed through both branches of the clasping-iron inside the embraced sill. 75

3. In combination with the tubular sills, the trusses connecting them formed of the upper 80 and lower bars and the connecting-clasps, said clasps bolted to the bars and bent around and pinched onto the sides and made wider than the bars throughout the portion which embraces the sills, whereby a more secure attachment to the sills is effected. 85

4. In combination with the tubular sills, the trusses connecting them formed of the upper and lower bars and the uniting-clasps, the upper bars flanged upward, and the upright posts 90 bolted to such flanges.

5. In combination with the front sill, the truss C², comprising the upper and lower bars and their connecting-clasps, and having said bars extended forward beyond the front 95 clasp to afford attachment for the pole.

6. In combination with the front sill, the truss C², comprising the upper and lower bars and the clasps connecting them, and having said bars extended forward beyond the front 100 clasp, the pole-pivot block bolted between the said extended bars, the shoes secured to the inner end of the sill and provided with the lug in line with the block, and the pole pivoted on the block and having a brace extended to the 105 lug.

7. In combination with the front and rear sills, the trusses connecting them on the grain side of the wheel, composed of the upper and lower bars, and the gearing-frame constituting 110 struts for the trusses.

8. The truss C², composed of the upper and lower bars having the inner segment and the gearing-frame as its struts.

9. In combination with the front and rear 115 sills and the two inside trusses connecting the sills and composed of the upper and lower bars, the gearing-frame made integral and secured rigidly to both trusses and constituting a horizontal brace between the trusses. 120

10. In combination with the two inside trusses composed of the upper and lower bars, the gearing-frame made integral and formed as struts for both said trusses and as a brace between them. 125

In testimony whereof we have hereunto set our hands, in the presence of two witnesses, at Chicago, Illinois.
